UNITED STATES PATENT OFFICE.

EMILE BOURDELLES, OF PARIS, FRANCE, ASSIGNOR OF ONE-HALF TO COMPAGNIE DES FORGES ET ACIERIES DE LA MARINE ET D'HOMECOURT, OF PARIS, FRANCE, A JOINT-STOCK COMPANY.

ELEVATION-CONTROLLED FIRING APPARATUS FOR GUNS.

1,096,673.

Specification of Letters Patent. Patented May 12, 1914.

Application filed September 26, 1913. Serial No. 791,972.

To all whom it may concern:

Be it known that I, EMILE BOURDELLES, a citizen of the Republic of France, resident of 39 Rue Galilée, Paris, France, have invented a new and useful Elevation-Controlled Firing Apparatus for Guns, which is fully set forth in the following specification.

This invention has for its object to provide a device for automatically firing breech loading guns at the moment at which they reach any desired elevation.

The invention is equally applicable to firearms and to larger guns such as ships' guns and also to guns whose elevation is caused to vary at the moment of firing by any means.

The invention consists broadly in utilizing a gravity controlled member connected to the gun, and in constructing this member in the form of an electrical make or break device arranged in the circuit of an electric firing mechanism or of an electro-mechanical or electromagnetic device for actuating the trigger.

In other words, the invention consists in the combination upon the gun itself or suitably connected therewith, of an electric firing device or of an electromagnetic or electromechanical device for actuating the trigger or the firing mechanism with a device for making the circuit by means of a member such as a level or pendulum, that is to say, a device which acts automatically merely under the influence of gravity.

By reason of the fact that the firing mechanism is automatically actuated by the electro-magnetic means located in an electric circuit controlled by gravity contact means, the actuation of the firing means is made independent of the marksman at the precise moment when the arm passes in elevation or depression the desired inclination.

Various practical embodiments of the invention applied to a portable firearm such as a military rifle are illustrated by way of example in the accompanying drawing:

In one embodiment of the invention illustrated in Figures 1 and 2, in longitudinal section and in elevation, it is assumed that firing is effected by means of a trigger connected with a sear and in accordance with the invention, actuated by mechanism subject to the influence of an electromagnet which is energized for the actuation by a

circuit which is automatically made when the pendulum or gravity controlled member reaches the proper position during the firing movement. Fig. 3 is a section on the line $x-x$ of Fig. 2; Figs. 4 and 5 illustrate detail constructional modifications. Figs. 6 and 7 are sections of modifications of the gravity controlled member which makes the circuit.

In the stock A of the gun or at any other convenient point, a source of electrical energy is provided. In the example here illustrated, this source of electricity is constituted by a battery a in the stock, the current from which passes to an electromagnet b also in the stock and to a mercury level c through the insulated terminal d , the point of which is immersed in the mercury when the level is horizontal. The current issues through an insulated terminal d' the point of which is regulated in such a manner that it is also immersed in the mercury at the same moment. The current then passes along a flexible wire e , connected with a movable contact f carried by a rod g . The level c which is hermetically closed, is provided with a tube c' enabling the air to pass from one vertical branch to the other. When (the rifle being about to assume the firing position) the marksman while depressing or raising the rifle presses upon a false trigger h and brings it as far as a suitably adjusted stop i , a spring j arranged between the false trigger h and the trigger proper u presses the latter and prepares the firing movement. At the same time the rod g moves rearwardly and the movable contact f rigidly mounted on the rod passes between spring jaws k connected with the extremity l of the winding of the electromagnet. When the rifle reaches the proper inclination the mercury of the level c , in simultaneously contacting with the two terminals d d' makes the automatic operating circuit. The magnetic attraction between the core b' of the electromagnet and an armature m then shifts the latter toward the butt of the stock. The armature m carries a finger m' against which a cross piece n normally rests; this cross piece is jointed at n' to a tube b^2 inclosing the electromagnet and through which the rod g passes freely. The spring o then presses the cross piece n into contact with the head p fixed at

the end of the rod g which has receded owing to the action of the marksman upon the false trigger h and this contact fires the rifle with the cumulative energy of the spring o and of the spring j . Owing to the movable contact f , the current is unable to flow and the rifle cannot be fired unless the false trigger h has previously been pressed by making the movement hitherto habitually employed.

10 In order to increase the sensitiveness of the mechanical relay formed by the members m and n and to permit of employing weak currents, as shown in the modification illustrated in Fig. 4, the lever $m m'$ can be formed in two parts, oscillating independently around one and the same pivot; the lever m is then provided with a snug m^2 producing a blow upon a tail m^3 of the finger m' at the end of the magnetic attraction.

15 Fig. 5 illustrates another modification of the mechanical relay, consisting of a plunger q acted upon by a spring r ; this plunger is maintained cocked by two claws $s s'$ which lock it in the position illustrated.

20 When the current passes it attracts the releasing device t whose movement owing to the action of the projections t' upon the claws $s s'$ releases the plunger which then strikes the head p of the rod g .

25 With the two types of relay illustrated in Figs. 1 and 5 when the marksman re-loads, the trigger proper u in moving forward exerts traction upon the rod g whose head p together with the coiled spring v replace all 30 the parts of the relay in the position which permits of firing. In order to fire the rifle at a varying elevation dependent upon the range of the target, the level c is carried by a bracket which can be given diverse inclinations by means of gear and rack $x x'$ (Fig. 1) controlled by a lever y (Fig. 2) mounted upon the shaft of the pinion w' .

35 For weapons firing ammunition with electric fuses, the entire system described above can be reduced to the battery and the level 40 suitably connected one with the other and with the fuse.

45 Fig. 6 illustrates in sectional elevation a modification of the device for making the 50 circuit by means of a controlled gravity member. A mercury drop level c is composed of two cylindrical steel elements 1 and 2, separated by a cylindrical portion 3 of fiber or ebonite fixed to a base z by a 55 collar 4 or other appropriate member; the drop of mercury might be replaced by a steel ball. In this case it is advantageous for the distance between the internal surfaces of the ebonite wall 3 to be greater 60 than that between the walls of the cylinders 1, 2. The base z , like the casing c of the level in the foregoing example, is pivoted to the stock and carries one of the members x , of the train for regulating the firing.

65 Fig. 7 represents another modification of

the device for making the circuit by means of a controlled gravity member. In this example the said member is a small pendulous mass 5 suspended at 6 by means of a shaft connected with one of the terminals of the source of electricity from a bracket 7 integral with the base z , and oscillating between an adjustable screw 8 and a terminal d' connected with the electromagnet and insulated from the support z .

70 In the examples that have been described, the device whereby the operating circuit is made by a gravity controlled member is wholly housed in the weapon itself. It will, however, be obvious, that in applying the invention to non-portable weapons such as ships' guns for example, the circuit making device might be fitted to the gun carriage, or at any other suitable place separated from the gun proper provided that it is connected with the latter in some appropriate manner. Although it is preferable that the automatic actuation of the trigger or the automatic firing mechanism should be produced by the closing of the interposed electrical device, it 80 is obvious that the desired result might also be obtained by breaking the circuit by means of some appropriate gravity switch.

85 The device described is applicable to the simultaneous operation from a central station of a plurality of guns connected with this station. In particular, it is applicable in combination with installations for the control from a distance of the sights of naval guns or stationary guns.

90 95 What I claim and desire to secure by Letters Patent of the United States is:—

1. In a gun, the combination of firing means, means held under tension for actuating said firing means, and gravity-controlled electromagnetic means adapted to set in operation said actuating means when the gun occupies a predetermined position in elevation or depression.

member, spring-pressed means normally restrained from acting on said member, electromagnetic releasing means for said spring-pressed member, and an energizing circuit 5 for said magnet including contacts controlled by said member and gravity controlled contacts adapted to be closed when the gun is in firing position.

5. In a gun, the combination of trigger 10 operated firing means, a trigger actuating member, spring-pressed means normally restrained from acting on said member, and gravity controlled means adapted to release said spring-pressed means to act on said 15 member when the gun occupies a predetermined firing position.

6. In a gun, the combination of trigger

operated firing means, a trigger actuating member, spring-pressed means normally restrained from acting on said member, electrically controlled means for releasing said restraining means including gravity controlled contacts and contacts controlled by 20 said actuating member, and a false trigger acting through said member to close one 25 set of said contacts, the other set being closed when the gun is in firing position.

In testimony whereof I have signed this specification in the presence of two subscribing witnesses.

EMILE BOURDELLES.
